UNITED STATES PATENT OFFICE

ROBERT T. MULLINS, OF BROOKLYN, NEW YORK, ASSIGNOR TO A. G. SPALDING & BROS., OF NEW YORK, N. Y., A CORPORATION OF NEW JERSEY

GOLF BAG

Application filed May 27, 1937. Serial No. 194,600.

This invention relates to golf bags of the type having a folding hood by which the bag may be completely closed and locked for security in shipping and storing.

5 A principal object is to provide a construction in which the hood folds down over the outside of the bag and in which means are provided whereby access may be had to both handle and shoulder strap in either closed 10 or open position of the hood.

A further feature of the invention involves the location of a ball pocket on the hood in such a position that it is exposed when the hood is opened and is shut inside the bag 15 when the hood is closed.

While a preferred form of the invention has been disclosed for purposes of illustration, it should be understood that various changes may be made in the structure without departing from the spirit and scope of the invention as hereinafter set forth and claimed.

In the drawings:

Fig. 1 is a perspective of a bag embodying 25 the invention, the hood being open.

Fig. 2 is a view similar to Fig. 1 with the hood closed.

Fig. 3 is a perspective view of the front side of the bag in open position.

30 Fig. 4 is a view similar to Fig. 3 with the hood closed.

Referring to the drawings more particularly, the reference numeral 10 indicates the main body of the bag, which includes a 35 leather bottom part 11 and a leather top part 12, the intermediate portion being composed of canvas or other suitable material and being reinforced by stiffening ribs 13 in a well-known manner. A handle 14 is attached to 40 the rear side of the bag near its upper end, and a shoulder strap 15 is adjustably secured at its lower end by a buckle 16 fastened to the lower part of the bag, the upper end of the strap being removably attached by a snap 45 fastener 17 to a ring 18 carried by the bag.

A reversible hood 19 has one end caught in the seam 20 which holds the leather top part 12 to the body of the bag. The hood has a slit extending vertically along its forward 50 side, across its top, and partly down its rear

side, as will be clear from Figs. 2 and 4. This slit is closed by a slide-actuated fastener, so arranged that the fastener is secured when the slide 21 is at the lower end of the slot as in Fig. 4. A ring 22 carried by the slide 55 is then in such position that it may be locked to a ring 23 on the body of the bag to prevent unauthorized opening of the bag.

When it is desired to open the bag and expose the clubs for use the upper end of the 60 carrying strap is first detached from the bag by releasing the snap fastener 17 from the ring 18. The slide 21 is then unlocked and moved to the end 24 of the slit, thereby releasing the slide fastener and permitting the hood 65 to be stripped down over the outside of the bag to the positions of Figs. 1 and 3, after which the snap 17 is again engaged with the ring 18. The strap 29, which is carried by one of the free edges of the hood, is then 70 engaged with the buckle 30 on the other free edge to hold these free edges against annoying movement while the bag is being carried.

A V-shaped notch 25 is cut into the lower 75 end of the hood, and the handle is so located in relation to the notch that it is accessible for carrying the bag whether the hood is open or closed. A slot 26 cut through the hood in the proper place allows ring 18 to project through the hood for attachment of the carrying strap when the hood is closed.

The ball pocket 27 is closed by a slide actuated fastener 28 and is secured to the side of the hood that is exposed when the hood is open. It is unnecessary to provide a separate lock for this pocket since it is completely shut within the hood when the latter is closed as in Fig. 4. In the improved bag set forth herein the folding hood need not be tucked down inside the bag when the clubs are to be used, as is necessary with conventional bags of this type. Instead, the hood is quickly stripped down over the bag and secured against flapping by the strap 29, the operation of closing and locking the hood being carried out with equal speed and facility. The location of the pocket is such that it is automatically shut within the bag or turned out to an accessible position during the closing or opening of the bag.

Another advantageous result of the structure disclosed herein lies in the fact that the notch 25 permits placing the handle 14 at the upper extremity of the bag so that the bag will balance properly for carrying by handle 14 when loaded with clubs.

I claim:

1. A golf bag comprising a main body, a collapsible hood attached to the upper end of the body, the hood being adapted to be moved to a closed position covering the upper end of the body or to an open position extending over the outside of the body, and a pocket attached to the hood in such a position as to be shut within the hood when the hood is in closed position and to be accessible when the hood is in open position. 70
2. A golf bag comprising a main body, a collapsible hood attached to the upper end of the body, the hood being adapted to be moved to a closed position covering the upper end of the body or to an open position extending over the outside of the body, and a pocket attached to the side of the hood that is innermost when the hood is in closed position. 75
3. A golf bag comprising a main body, a collapsible hood attached to the upper end of the body, the hood having a slit extending along one side and across its top to form two flaps, the hood being movable to a position above the top of the bag, means for fastening the edges of the slit together to close the bag, the hood being movable to an open position extending over the outside of the body, and a pocket attached to the side of the hood that is innermost when the hood is in closed position. 80
4. A golf bag comprising a main body, a collapsible hood attached to the upper end of the body, the hood having a slit extending along one side and across its top to form two flaps, the hood being movable to a position above the top of the bag, means for fastening the edges of the slit together to close the bag, the hood being movable to an open position extending over the outside of the body, means for securing the flaps in open position, and a pocket attached to the side of the hood that is innermost when the hood is in closed position. 85
5. A golf bag comprising a main body, a collapsible hood attached to the upper end of the body, the hood having a slit extending along one side and across its top to form two flaps, the hood being movable to a position above the top of the bag, a slide-actuated fastener for securing the edges of the slit together to close the bag, the hood being movable to an open position extending over the outside of the body, means for securing the flaps in open position, and a pocket attached to the side of the hood that is innermost when the hood is in closed position, the pocket being accessible when the hood is in open position. 90
6. A golf bag comprising a main body, a collapsible hood attached to the upper end of the body, the hood having a slit extending along one side and across its top to form two flaps, the hood being movable to a position above the top of the bag, a slide-actuated fastener for securing the edges of the slit together to close the bag, the hood being movable to an open position extending over the outside of the body, a pocket attached to the side of the hood that is innermost when the hood is in closed position, the pocket being accessible when the hood is in open position, and means for closing the pocket. 95
7. A golf bag comprising a body having an open end, a carrying handle attached to the body adjacent the open end of the body, a hood formed of flexible material and attached about the outside of the body along a line located intermediate the ends of the handle, the side of the hood opposite the handle being slit to permit closing the hood over the open end of the body or stripping the hood down over the outside of the body, means for closing the hood along the slit, the hood being formed with a cut-out about the handle, the carrying handle passing through the cut-out in both of said positions of the hood. 100
8. A golf bag comprising a body having an open end, a carrying handle attached to the body adjacent the open end of the body, a shoulder strap having one end attached to the body below the carrying handle, a securing element fastened to the body above the carrying handle and adapted for detachable connection with the other end of the shoulder strap, a hood formed of flexible material and attached about the outside of the body adjacent the handle, the side of the hood opposite the handle being slit to permit closing the hood over the open end of the body or stripping the hood down over the outside of the body, means for closing the hood along the slit, the hood being formed with a cut-out to permit exposure of the handle, the hood being formed with a second cut-out, spaced from the first cut-out and affording access to said securing element to permit attaching the end of the shoulder strap to said securing element. 105
9. A golf bag comprising a body having an open end, a carrying handle attached to the body adjacent the open end of the body, a shoulder strap having one end attached to the body below the carrying handle, a securing element fastened to the body above the carrying handle and adapted for detachable connection with the other end of the shoulder strap, a hood formed of flexible material and attached about the outside of the body along a line located intermediate the ends of the handle, the side of the hood opposite the handle, the side of the hood opposite the handle. 110
10. A golf bag comprising a body having an open end, a carrying handle attached to the body adjacent the open end of the body, a shoulder strap having one end attached to the body below the carrying handle, a securing element fastened to the body above the carrying handle and adapted for detachable connection with the other end of the shoulder strap, a hood formed of flexible material and attached about the outside of the body along a line located intermediate the ends of the handle, the side of the hood opposite the handle, the side of the hood opposite the handle. 115
11. A golf bag comprising a body having an open end, a carrying handle attached to the body adjacent the open end of the body, a shoulder strap having one end attached to the body below the carrying handle, a securing element fastened to the body above the carrying handle and adapted for detachable connection with the other end of the shoulder strap, a hood formed of flexible material and attached about the outside of the body along a line located intermediate the ends of the handle, the side of the hood opposite the handle, the side of the hood opposite the handle. 120
12. A golf bag comprising a body having an open end, a carrying handle attached to the body adjacent the open end of the body, a shoulder strap having one end attached to the body below the carrying handle, a securing element fastened to the body above the carrying handle and adapted for detachable connection with the other end of the shoulder strap, a hood formed of flexible material and attached about the outside of the body along a line located intermediate the ends of the handle, the side of the hood opposite the handle, the side of the hood opposite the handle. 125
13. A golf bag comprising a body having an open end, a carrying handle attached to the body adjacent the open end of the body, a shoulder strap having one end attached to the body below the carrying handle, a securing element fastened to the body above the carrying handle and adapted for detachable connection with the other end of the shoulder strap, a hood formed of flexible material and attached about the outside of the body along a line located intermediate the ends of the handle, the side of the hood opposite the handle, the side of the hood opposite the handle. 130

handle being slit to permit closing the hood over the open end of the body or stripping the hood down over the outside of the body, means for closing the hood along the slit, the hood being formed with a cut-out about the handle to permit exposure of the handle in either of said positions of the hood, the hood being formed with a second cut-out, spaced from the first cut-out and affording access to said securing element to permit attaching the end of the shoulder strap to said securing element.

10. A golf bag comprising a body having an open end, a carrying handle attached to the body adjacent the open end of the body, a shoulder strap having one end attached to the body below the carrying handle, a securing ring fastened to the body above the carrying handle and adapted for detachable connection with the other end of the shoulder strap, a hood formed of flexible material and attached about the outside of the body along a line located intermediate the ends of the handle, the side of the hood opposite the handle being slit to permit closing the hood over the open end of the body or stripping the hood down over the outside of the body, means for closing the hood along the slit, the hood being formed with a cut-out about the handle to permit exposure of the handle in either of said positions of the hood, the hood being formed with a second cut-out, spaced from the first cut-out and permitting exposure of the securing ring for connection with the end of the shoulder strap.

In testimony whereof I affix my signature.
ROBERT T. MULLINS.
